HOWARD N. JONES, OF PROVIDENCE, RHODE ISLAND, ASSIGNOR OF ONE-HALF TO
GEORGE H. COTE, OF PROVIDENCE, RHODE ISLAND.

SELF-OPENING DIE-HOLDER.

1,316,619.

Specification of Letters Patent. Patented Sept. 23, 1919.

Application filed February 25, 1918. Serial No. 219,044.

To all whom it may concern:

Be it known that I, HOWARD N. JONES, a citizen of the United States, residing at Providence, in the county of Providence and State of Rhode Island, have invented 5 certain new and useful Improvements in Self-Opening Die-Holders, of which the following is a specification.

My invention relates to improvements in 10 self opening die-holders, and the purpose of my invention is to provide a die-holder which is capable of utilizing the ordinary circular or "button" die, such as is kept in stock at ordinary hardware stores, and 15 which will open automatically and release the bolt or other work on which the thread is to be cut at any predetermined point.

I also aim to provide a die-holder which will give larger clearance for chips than is 20 provided by die-holders now in use.

In nearly or quite all of the automatic or self opening die-holders or automatic thread-cutters now in use, either special cutters have to be used in the place of dies, or 25 specially made dies have to be utilized, thus making an automatic die-holder a very expensive tool. One of my purposes is to greatly reduce the cost of such a holder by the utilization with slight modifications of 30 the ordinary commercial circular or "button" die.

I accomplish these objects by the mechanism shown in the accompanying drawings, in which—

35 Figure 1 is a front view of my die-holder; Fig. 2 a vertical section through the holder lengthwise;

Fig. 3 a vertical section in a plane at right angles to the section shown in Fig. 2;

40 Fig. 4 a detail of the die-holder;

Fig. 5 a front view of my device showing the dies open;

Fig. 6 a vertical section of my improvement showing the inclosed bolt on which the 45 thread is being cut, and

Fig. 7 a vertical section of the same in a plane at right angles to the section shown in Fig. 6.

In Fig. 1, A represents a hollow cylindrical shell of metal open at one end and partly closed at the other, as shown best in Fig. 2. Fitting slidably within this shell is the member B which is similar in shape

to A and comprises a similar hollow cylindrical shell which carries upon it the die-holder proper E—E. 55

C, in Figs. 2 and 3, represents the tail piece or shank adapted to be fitted to a turret or tail stock of a lathe or other suitable machine and A is securely fastened to 60 C by the bolts c—c.

As shown in Fig. 2, the holes a in the flange a' of the tail piece C through which the bolts c extend are made larger than the diameter of said bolts so as to allow for adjustment of the die-holding means proper relative to the tail piece C to thereby compensate for any lack of concentricity of the "button" die.

The member B has also a bottom piece, 70 shown at b—b which is secured to the member B by the screws b' seen in Figs. 2 and 6.

d—d represent an ordinary "button" die which in order for adaptation to my holder is simply split in two diametrically. 75

E—E seen best in Figs. 1 and 4 is the die-holder proper and consists substantially of the two semi-circular members, E—E, Fig. 4, hinged upon the spindle e, Fig. 1, so as to be capable of being separated, as shown in 80 Fig. 5.

The opposite ends of the holder E—E are modified, as shown in Fig. 4, having the slot e'—e' cut in the outside faces for the accommodation of the spring e'', Fig. 1, 85 which operates to open the holder E—E with the inclosed halves of the die and release the work at the desired point.

The inner faces of the extremities of the die-holder E—E adjacent to the hinge e are 90 beveled, as shown in e"—e", Fig. 4, so as to form a suitable bearing for the wedge-shaped member, V, shown in Fig. 1, by means of which the dies may be closed through the ball handle O. 95

c"—c' in Fig. 1 is a cap secured to the member B by the screws F"—F' for the purpose of retaining the outer extremities F of the die-holder E shown in Figs. 1 and 5, a portion of the shell A being cut away at 100 the point f forming an embrasure, as shown in Fig. 1 in plan and shown in Figs. 2 and 6 vertically, so as to accommodate the ends F—F of the die-holder E—E.

In Fig. 6 the die-holder E—E is shown 105 with its outer ends F—F wholly outside the

cut-away portion *f* while in Fig. 2 the die-holder is shown with its outer extremities partially within the cut-away portion *f*.

c''—c'', Fig. 1, are adjusting blocks 5 screwed to the shell *A* in the cut-away portion aforesaid, and having the adjusting screws *c'''—c'''* which enable the operator to adjust the degree of opening of the die *d—d* in its operation.

10 The halves *d—d* of the die are retained in the holder by means of the screws *g'—g'* and the pins *g—g*, shown in Figs. 1 and 5.

H—H' are screws going through the side of the shell *A* and penetrating longitudinal recesses *L—L* in the inner member *B*, as shown in Figs. 1, 3 and 7. Within these recesses, as shown in Figs. 3 and 7, are spiral springs *S—S*, retained in place by the cap *b* of the member *B* at one end, and the bushings *h—h* 20 upon the inner ends of the screws *H—H'* at the other end. These recesses *L—L* with their inclosed springs are situated at opposite points in the wall of *A*, as shown best in Figs. 1 and 5, and the springs operate to 25 normally keep the member *B* at its innermost position within the shell *A*. The spring *s* secured to the interior of the bottom of *A* serves as a slightly resisting cushion to the member *B*, and enables a bolt on 30 which a single cut has been made to properly engage the die on a second cut.

The wall of the inner member *B* is pierced by the holes *J—J*, shown in Figs. 2, 3, 6 and 7, and there are corresponding holes *K—K*, 35 etc., in the outer shell *A*, shown in the same figures.

Inasmuch as rotation of *B* within *A* is prevented by the screws *H—H* sliding in the recess in *B* above mentioned, the holes 40 *J—K* cannot get wholly out of opposition, and these holes provide ample means for the discharge of chips from the dies which would otherwise accumulate and clog the interior.

45 The lever *V'* is secured to the outer wall of the shell *A* by the hinge support *v''*, shown best in Figs. 2 and 6. This lever *V'* is provided with the ball handle *O* and the wedge-shaped portion *V*, shown in Figs. 1 50 and 2. The lever *V'* operates to close the dies when it is desired to do so, by pressing the wedge-shaped member *V* down upon the extremities of the holder *E* adjacent to the hinge *e* thereof.

55 *W* in Figs. 2, 3, 6 and 7 represents the bolt or work on which the thread is to be cut.

In Figs. 2 and 3 this is shown as not yet having entered the die, while in Figs. 6 60 and 7 it is shown wholly within the die-holder, the thread being cut thereon.

I in Figs. 2 and 6 represents a guide fastened to a suitable standing part of the machine and serving to close the dies automatically 65 when the die-holder is withdrawn

from the bolt or work on which the thread is cut. This guide is beveled upon the face I and upon impingement upon the ball *O*, as shown in Fig. 2, depresses the lever *V'* thus closing the dies and holder and preparing 70 the same for the cutting of a new bolt or thread.

My device operates as follows:—

The die-holder is suitably fastened to the tail piece of the machine or to a reciprocating turret, and the work on which the thread is to be cut is secured to the head stock of the lathe or machine. The turret is then pushed forward so as to engage the bolt in the die in the usual manner, the die-holder 75 being closed and the member *B* being at the bottom or innermost position in the shell *A* by means of the springs *S—S*. As the thread is cut by the die, the turret slides forward toward the head stock or spindle of 80 the machine, and the bolt enters the member *B*. At a suitable predetermined point, the travel of the turret stops, but the thread on the revolving bolt continues to draw upon the member *B* and draws it forward until 85 the outer extremities *F—F* of the die-holder are drawn forward and disengaged from the embrasure *f* formed by the blocks *c''—c''*. The instant these ends *F—F* are released from the embrasure *f* they are automatically 90 opened by the spring *e''*, thus releasing the work from the die and the entire holder with the die is drawn back by the retiring turret. As it recedes, the guide *I* with the beveled face, operating upon the ball *O* of the lever 95 *V'* closes the holder *E—E* automatically and the holder is ready for a new bolt.

I am aware that prior to my invention automatic or self opening die-holders have been in use, but so far as my knowledge 105 extends such die-holders cannot utilize the ordinary commercial round die or any modification thereof, but are confined to special cutters of special dies which are costly and not kept in stock ordinarily by dealers.

In all the self opening die-holders known to your applicant the cutting mechanism occupies so much space that there is only a very little room for chips resulting in the machines becoming constantly clogged; 115 whereas by my device there is ample room for the accumulation and escape of all possible chips so that the die is kept clear.

Automatic die-holders as ordinarily used are very expensive, whereas my device is 120 capable of being constructed very cheaply; and in case of the breaking of a die it may be immediately replaced by the ordinary circular or "button" die by simply splitting the die in two equal halves diametrically.

Having now described my invention, what I claim and desire to secure by Letters Patent is:—

1. A self opening die-holder comprising a shell, a spindle arranged longitudinally of 130

- the shell, transversely arranged paired members at one end of the shell pivoted at one end on said spindle and adapted to receive and hold the halves of a "button" die, means 5 for the automatic opening of said holders and die, means for adjusting the holders and die to vary the cutting area thereof, and means carried by the shell for automatically closing the free ends of said holders, substantially as described. 10
2. A self opening die comprising a pair of telescopically associated members, a pair of die holders pivotally connected at one end to one of said members, and means carried 15 by the other said member for engagement with the free ends of said holders whereby said holders may be adjusted to and from one another, substantially as described. 15
3. A self opening die comprising inner and outer members, means connecting the inner member to the outer member and normally retaining said inner member in its innermost position, a pair of die holders pivoted to the inner member, means for the 20 retention and automatic release and separation of said die holders, substantially as described. 25
4. A self opening die holder comprising an outer member, an inner member slidably 30 fitted in the outer member, means slidably connecting the members together, means for normally retaining the inner member in its innermost position within the outer member, and a cushioning member located between the inner and outer members, substantially as described. 35
5. A self opening die holder comprising telescopically associated inner and outer members, a pair of die holders pivoted at 40 one end to said inner member, adjusting means carried by the outer member for engagement with the free ends of the holders whereby they may be adjusted toward and away from one another, and means at the 45 pivot ends of said holders to permit of the automatic opening of said die holders at any stage of the cutting operation, substantially as described. 50
6. A self opening die holder comprising inner and outer members, a pair of die 55 holders pivotally connected together at one of their ends in the inner member, said outer member provided with a recess receiving the free ends of said holder members when in one position, and spring means engaging said die holders to automatically open the latter when the inner member is extended. 60
7. A self opening die holder comprising inner and outer members, a pair of die 65 holders pivotally connected together at one of their ends in the inner member, said outer member provided with a recess receiving the free ends of said holder members when in one position, means at the pivoted ends of said holders to open the latter when the inner member is extended, means to retract the inner member, and means to automatically close the holders upon the retracting of the inner member, substantially as described. 70
8. A self opening die holder comprising telescopically mounted inner and outer members, means slidably connecting the inner and outer members and holding the members against relative rotation, a resilient member carried by the inner member and engaging the holding means to normally retain the inner member in its innermost position within the outer member, die holders 75 carried by the inner member, and means for the retention and automatic release and separation of the die-holders operable upon relative movements of said inner and outer members. 80
9. A self opening die holder comprising inner and outer members, means slidably connecting the members together, a spindle carried by the inner member, a sectional die holder pivoted to the spindle, adjusting means secured to the outer member and engaging the free ends of the sectional die holder whereby the cut of the die may be adjusted, substantially as set forth. 85
10. A self opening die holder comprising inner and outer members, means slidably connecting the members together, a pair of "button" die holders pivotally connected together and to the inner member, adjusting means secured to the outer member and engaging the die holder for adjusting the cut of the latter, means secured to the die holders adjacent their pivoted ends to automatically open the same when the inner member is extended, and a wedge-shaped member pivoted at one end to the outer member and engaging the pivoted end of the holder with its free end to automatically close the latter when the inner member is retracted, substantially as described. 95
11. A self opening die holder including an inner and an outer member, means slidably connecting the members together, die holders pivoted to the inner member, means to automatically open said die holder, means to automatically close said die holder, and a cushion element located between said inner and outer members to assure proper registration between the die and the work when a subsequent cut is made. 100
12. A self-opening die-holder including yieldingly telescoped inner and outer members, separable transversely swinging die-holders pivotally carried by the inner member, yieldable means to normally separate said die-holders, and means carried by the outer member to engage the free ends of the die-holders and hold the latter closed, said inner member being movable outwardly of the outer member to automatically dis- 105
- 110
- 115
- 120
- 125
- 130

engage the free ends of die-holders from their holding means upon cessation of feeding during the threading operation.

13. In a die holder, a shell member having a button die supporting means associated therewith and provided with a flat rear wall, a tail piece provided with an outwardly directed annular flange forming a flat end wall contiguous with said rear wall of said member, one of said walls having a plurality of apertures therethrough, and bolts having shanks loosely extending through said apertures and threaded into the other wall to permit relative lateral adjustment of the member and the tail piece for compensating for lack of concentricity of the die and to secure the member and the tail piece against relative movement after the adjustment securing concentricity has been had.

14. A self-opening die holder comprising a shell, a spindle arranged longitudinally of the shell, transversely swinging paired members at one end of the shell pivoted at one

end on said spindle and adapted to receive and hold the halves of a button die, means 25 for automatically opening said holders and die, and means carried by the shell for automatically closing the free ends of said holders.

15. A self-opening die holder comprising 30 telescopically mounted inner and outer members, a resilient means to normally retain the inner member in its innermost position within the outer member, and transversely swinging separable die holders pivotally secured to the inner member, and means for the retention and automatic release and separation of the die holders operable upon relative movements of said inner and outer members.

In testimony whereof I affix my signature in presence of two witnesses.

HOWARD N. JONES.
